(57) **CLAIM**

The ornamental design for a teapot with a glass lid as shown and described.

DESCRIPTION

1. Teapot with glass lid

1.1 : Perspective

1.2 : Front

1.3 : Back

1.4 : Right

1.5 : Left

1.6 : Top

1.7 : Bottom

1.8 : Perspective

The present design relates to a teapot with a glass lid comprising an opaque vessel with a corrugated outer surface and an essentially transparent, dome-shaped, externally corrugated, glass lid; the vessel comprises a bulging base portion and an upper frustoconical portion diverging upwardly and forming a protruding pouring spot; a handle extends from the top of the vessel to the base portion; the black background, shadows and reflections shown in reproductions are disclaimed.

1 Claim, 8 Drawing Sheets
